CATALYTIC HYDROGENATION OF VISCOSITY BROKEN HYDROCARBON OILS
Harold Beuther, Gibsonia, Richard A. Flinn, Penn Hills Township, Allegheny County, and Bruce K. Schmid, McCandless Township, Allegheny County, Pa., assignors to Gulf Research & Development Company, Pittsburgh, Pa., a corporation of Delaware
No Drawing. Filed Feb. 16, 1961, Ser. No. 89,666
4 Claims. (Cl. 208—68)

This invention relates to the treatment of heavy hydrocarbons and in particular to the preparation of more valuable hydrocarbons from residual stocks.

Heavy hydrocarbons and residual stocks are of relatively low value as compared with the more volatile components of petroleum. These low value materials are usually employed as low grade fuels or are subjected to treatments such as visbreaking to obtain a certain amount of more valuable components and tar-like residues which may be used for roof or road surfacing materials. Also these low grade fractions of petroleum have been subjected to hydrogenation under various conditions in the presence of various catalysts. Although these procedures result in more or less improvement in yields or in the properties of certain portions of the material treated, there is still considerable room for lowering the cost of such treatments and upgrading of the products thus produced.

This invention has for its object to provide improved procedure for preparing more valuable hydrocarbons from low grade petroleum or fractions thereof having a relatively low API gravity. Another object is to provide improved procedure for preparing higher quality fuel oils in higher yield from low quality residues having an API gravity below about 20. A still further object is to provide an improved combination process for upgrading of residual stocks by visbreaking followed by hydrogenation treatment of a type which results in formation of a substantial amount of lower boiling components with concomitant hydrodesulfurization. This procedure may be referred to as either destructive hydrogenation or hydrodesulfurization. A still further object is to improve the state of the art. Other objects will appear hereinafter.

These and other objects of our invention are accomplished by subjecting crude petroleum or a residual fraction thereof having an API gravity below about 20 to a moderate visbreaking to form below about 15 percent gasoline, and subjecting the visbroken product to destructive hydrogenation or hydrodesulfurization catalyst at a pressure between about 500 and 5,000 p.s.i.g. and at a temperature between about 650° and 820° F. The hydrogen-hydrocarbon ratio during this destructive hydrogenation is maintained between about 1000 and 20,000 s.c.f./bbl. of hydrocarbon charge.

The residual feed stock used in our process may be any crude petroleum having an API gravity below about 20 or any residual fraction thereof having an API gravity of below about 20. There are many crudes which are very viscous and high in asphaltic content and we contemplate the treatment of such crudes without removal of any of their components when they have a gravity below about 20. On the other hand, most crudes are of higher gravity and with such crudes it is desirable to remove valuable portions thereof in conventional manner and

2

to obtain a residual fraction having a gravity below about 20. This residual fraction may be prepared by atmospheric or vacuum distillation.

The visbreaking operation may be any such operation known in the prior art. These visbreaking operations are commonly carried out by passing the charge stock through a heating coil and heating the oil to thermal cracking temperature. The time of heating, the pressure and the temperature of heating control the amount of thermal cracking or conversion into lower boiling components such as gasoline. In general the temperature may be between about 850° and 975° F., the heating time between about 250 and 1,000 seconds, and the pressure between about 50 and 6,000 p.s.i.g. The conditions are selected so as to result in a moderate degree of cracking, i.e. so as to form less than 15 percent gasoline. It is advantageous to form between about 1 and 15 percent gasoline and preferably between about 5 and 12 percent gasoline. Visbreaking procedures are described in standard textbooks and reference is made thereto for further details on this procedure. See for instance Sachanen, Conversion of Petroleum, Second Edition, Reinhold Publishing Corporation, 1948, pages 252-254. After visbreaking the product is preferably subjected to distillation to remove lower boiling components. We prefer to remove all gasoline and lower boiling components formed during the visbreaking step. However such removal is not necessary and all of the visbroken material may be subjected to the subsequent destructive hydrogenation if desired. With sulfur containing stocks this is advantageous since the lower boiling components which contain sulfur will also be desulfurized during the subsequent destructive hydrogenation.

The visbroken residual stock is contacted with hydrogen in the presence of a catalyst such as an oxide or sulfide of a Group VI left-hand column metal of the Periodic System. Similarly metals of the iron group, their oxides and sulfides may be employed as catalysts. These Group VI and iron group catalysts may be mixed with one another. For instance an advantageous mixture is a mixture of cobalt and molybdenum oxides or sulfides. Another advantageous mixture is a mixture of nickel and tungsten oxides or sulfides. These catalysts are deposited upon a porous catalyst carrier. Typical useful catalyst carriers are activated alumina, pumice, a silica-alumina cracking catalyst, etc. The pressure during the destructive hydrogenation is maintained between about 500 and 5,000 p.s.i. and preferably is between about 1,000 and 2,000 p.s.i. The temperature may be between about 650° and 820° F. A space velocity between about 0.2 and 10.0 volumes of charge stock per hour per volume of catalyst may be used. As will appear hereinafter, the coupling of moderate visbreaking with a rather severe type of hydrodesulfurization has definite advantages in that the amount of coke deposited during the hydrodesulfurization is greatly reduced as compared with hydrodesulfurization of the same severity applied to a straight run stock or to a more severely visbroken stock. For this reason we prefer to employ relatively severe temperature conditions of between about 750° and 790° F. with a space velocity of between about 0.5 and 4.0 for the destructive hydrogenation or hydrodesulfurization. The hydrogen is present during the reaction in a ratio of between about 1,000 and 20,000 standard cubic feet and preferably between about

2,000 and 10,000 standard cubic feet per barrel of vis-broken-deasphalted residual charge stock.

A preferred mode of destructive hydrogenation or hydrodesulfurization as indicated above, is to utilize a pressure of about 1000 p.s.i. This pressure is a moderate pressure as compared with pressures heretofore used in destructive hydrogenation. Therefore the cost of the equipment is considerably lower than required for such prior destructive hydrogenation equipment. Alternatively we may operate in accordance with our invention by utilizing a pressure of between about 2000 and 3500 p.s.i. to obtain more thoroughgoing conversion into a product which is an excellent catalytic cracking charge stock. These pressures are still moderate as compared with those previously used for destructive hydrogenation. Therefore this conversion to catalytic cracking stock is accomplished without using the relatively high pressures of the destructive hydrogenation prior art. However it is entirely feasible to obtain high yields of fuel oils of improved quality, especially of low sulfur content, by carrying out the hydrogen treatment at any pressure between about 500 and 5000 p.s.i.

The following example illustrates the benefits obtained by operating in accordance with our invention.

EXAMPLE

A vacuum residue obtained from a mixture of Kuwait and Venezuela crudes having the properties shown in Table I was contacted with hydrogen in the presence of a nickel-cobalt-molybdenum catalyst deposited on alumina under the conditions shown in columns 1 and 2 of Table II. The results are given in columns 1 and 2 of Table II.

Products produced as described above were subjected to distillation at atmospheric pressure to remove volatile products in a conventional manner. The atmospheric residue thus obtained was then subjected to distillation to obtain a 670° F. residue and a 1000° F. residue. The properties of the 670° and 1000° F. residues thus obtained are given in Table III.

A vacuum residue obtained by vacuum distillation of a mixture of Kuwait and Venezuela crudes and having the properties shown in Table IV was subjected to vis-breaking at three different severities to form gasoline in amounts of 3 percent, 11.8 percent and 20.5 percent respectively. After removal of the gasoline a part of the residues from each visbreaking operation was contacted with the same nickel-cobalt-molybdenum catalyst mentioned above in the presence of hydrogen under three different severities (temperatures of 700°, 750° and 790° F.) and under the conditions given in Table V. The results of the visbreaking operations as well as the hydrogen treatments are given in Table V.

¹ Solid gravity, 77°/77° F.² Beyond scope of method.

The above data show that our invention gives high yields of gasoline, furnace oil and a #6 fuel oil having a low sulfur content. Also these data show that the invention gives a high yield of distillate products and a low yield of #6 fuel oil and coke as compared with the other procedures. For instance it will be noted from the above data that in connection with moderate visbreaking followed by hydrodesulfurization or destructive hydrogenation at more severe conditions of 750° to 790° F., there was no increase in coke formation. This is to be compared with a marked increase in coke deposition when a severely visbroken feed is hydrodesulfurized at 750° F. (column 9 of Table V.) This is also to be compared with Table II where the coke deposition from a straight run feed increased considerably on a temperature increase from 750° to 790° F. We have also found that the cyclic content of the products produced by our procedure is higher than that produced by alternative procedures.

We claim:

1. The process which comprises subjecting a member of the group consisting of crudes, reduced crudes and topped crudes having an API gravity to below about 20° to moderate visbreaking to form between about 1 and 15 percent gasoline and subjecting at least the gasoline-free portion of the visbroken material to treatment with hydrogen in the presence of a catalyst selected from the group consisting of oxides and sulfides of a metal of Group VI left-hand column and the iron group, at a pressure between about 1000 and 2000 p.s.i., at a temperature between about 650° and 820° F., at a space velocity between about 0.2 and 10 volumes of charge per volume of catalyst per hour, and at a hydrogen recycle rate of between about 1000 and 20,000 standard cubic feet per barrel of visbroken hydrocarbon charge stock.

2. The process which comprises subjecting a member of the group consisting of crudes, reduced crudes and topped crudes having an API gravity of below about 20° to moderate visbreaking to form between about 1 and

15 percent gasoline and subjecting at least the gasoline-free portion of the visbroken material to treatment with hydrogen in the presence of a catalyst selected from the group consisting of oxides and sulfides of Group VI left-hand column and the iron group, at a pressure between about 2000 and 3500 p.s.i., at a temperature between about 650° and 820° F., at a space velocity between about 0.2 and 10 volumes of charge per volume of catalyst per hour, and at a hydrogen recycle rate of between about 1000 and 20,000 standard cubic feet per barrel of visbroken hydrocarbon charge stock.

3. The process which comprises subjecting a member of the group consisting of crudes, reduced crudes and topped crudes having an API gravity of below about 20° to moderate visbreaking to form between about 3 and about 12 percent gasoline and subjecting at least the gasoline-free portion of the visbroken material to treatment with hydrogen in the presence of a catalyst comprising essentially a mixture of a member of the group consisting of Group VI oxides and sulfides with a member of the group consisting of iron, cobalt and nickel oxides and sulfides, deposited upon a porous carrier, at a pressure between about 500 and 5000 p.s.i., at a temperature of between about 750° and 790° F., at a space velocity between about 0.5 and 4.0 volumes of charge per volume of catalyst per hour, and at a hydrogen recycle rate of between about 2000 and 10,000 standard cubic feet per barrel of visbroken hydrocarbon charge stock.

4. The process which comprises subjecting a member of the group consisting of crudes, reduced crudes and topped crudes having an API gravity of below about 20° to moderate visbreaking to form about 12 percent gasoline and subjecting at least the gasoline-free portion of the visbroken material to treatment with hydrogen in the presence of a catalyst, comprising essentially a mixture of a member of the group consisting of Group VI oxides and sulfides with a member of the group consisting of iron, cobalt and nickel oxides and sulfides, deposited upon a porous carrier, at a pressure between about 500 and 5000

p.s.i., at a temperature of between about 750° and 790° F., at a space velocity between about 0.5 and 4.0 volumes of charge per volume of catalyst per hour, and at a hydrogen recycle rate of between about 2000 and 10,000 standard cubic feet per barrel of visbroken hydrocarbon charge stock.
